UNITED STATES PATENT OFFICE.

ROBERT BROTZ, OF PHILADELPHIA, PENNSYLVANIA, ASSIGNOR TO THE
CATERSON & BROTZ COMPANY, OF SAME PLACE.

PAPER BOX.

SPECIFICATION forming part of Letters Patent No. 329,134, dated October 27, 1885.

Application filed August 31, 1885. Serial No. 175,745. (No model.)

To all whom it may concern:

Be it known that I, ROBERT BROTZ, a citizen of the United States, residing in Philadelphia, Pennsylvania, have invented certain 5 Improvements in Paper Boxes, of which the following is a specification.

My invention relates to that class of paper boxes which are intended for the reception of a pack of cards, a plug of tobacco, or other contents which completely fill the box, the object 10 of my invention being to so construct such a box that the contents can be readily removed without overturning and shaking the box, as usual. This object I attain in the manner which I 15 will now proceed to describe, reference being had to the accompanying drawings, in which—

Figure 1 is a perspective view of my improved box, showing how the contents of the same can be grasped in order to withdraw 20 them; Fig. 2, a transverse section of the box, and Fig. 3 a perspective view of the box, showing modifications of my invention.

The box, so far as regards its general structure, is similar to boxes now made, and comprises the bottom *a*, front and rear sides, *b b*, opposite ends *d d*, and top *f*, with tuck-flap *g*, the whole being preferably made from a single blank scored, folded, and pasted in the ordinary manner. Such boxes usually have 25 a thumb-notch cut in the upper edge of the front side, *b*; but this thumb-notch is of little avail, as the finger cannot be inserted between the rear side of the box and the contents of the same in order to permit the contents to 30 be grasped between the thumb and finger when it is desired to withdraw said contents from the box. In order to overcome this objection, I cut away both the front and rear sides of the box at the top, so that the contents of the box can be grasped between the thumb at the front and the forefinger at the rear as shown in Fig. 1, and the said contents thereby

readily withdrawn. The recessing of the rear side of the box is preferably effected by slitting the opposite corners of the rear of the 45 box for some distance from the top of the same, and then scoring the rear side of the box transversely at the lower ends of these slits, so that the upper portion of the rear side of the box forms a flap, *h*, which closes the recess when 50 the cover of the box is down and the flap *g* tucked into the slit in the front side of the box, the flap readily yielding, however, to the pressure of the finger when it is desired to remove the contents of the box. While this 55 plan of forming the recess is preferable, it is not absolutely necessary to the proper carrying out of my invention. For instance, an opening may be made in the rear side of the box and in the top, as shown in Fig. 3, and, 60 if desired, a yielding flap may be formed on the front side of the box, as also shown in said figure, this flap taking the place of the usual thumb-notch. (Shown in Fig. 1.)

I claim as my invention—

1. A paper box having a lid or cover connected to the rear side of the box, and having both the front and rear sides of the box cut away at the top, so as to permit the contents of the box to be grasped between the thumb and 70 finger in order to withdraw the same, as set forth.

2. The box having the front side cut away at the top, and a rear side also cut away and forming a yielding flap, *h*, connected to the 75 lid of the box, as specified.

In testimony whereof I have signed my name to this specification in the presence of two subscribing witnesses.

ROBT. BROTZ.
